UNITED STATES PATENT OFFICE.

WILLIAM H. CHAPMAN AND WALTER W. CHAPMAN, OF NEWARK, NEW JERSEY; SAID
WALTER W. CHAPMAN ASSIGNOR TO SAID WILLIAM H. CHAPMAN.

PRESS.

1,139,845.

Specification of Letters Patent. Patented May 18, 1915.

Application filed December 22, 1913. Serial No. 808,097.

To all whom it may concern:

Be it known that we, WILLIAM H. CHAPMAN and WALTER W. CHAPMAN, citizens of the United States, and residents of Newark, 5 in the county of Essex and State of New Jersey, have invented certain new and useful Improvements in Presses, of which the following is a specification.

This invention relates to improvements in 10 a press and its specific novelty comprises adjustable means for controlling the length of the down stroke of the slide of the press and consequently the punch or male die thereof.

In the accompanying drawings Figure 1 15 represents a side elevation of a press with the invention incorporated therewith, Fig. 2 is a partial left hand side view of Fig. 1, Fig. 3 is a top plan view of Fig. 1, Fig. 4 shows a top plan view of a detail and Fig. 20 5 shows a bottom view of Fig. 4.

The press is shown comprising the legs 20 supporting the table 21 and upon the latter is secured the frame having the two main members 22. The latter have formed there- 25 with the bolster bed 25, the guide 26 and the lugs 27.

Between the members 22 is located the 30 foot lever 30, which has formed at its upper end the disk head 31 with the cavity 32, and from its lower end extends the foot 33.

A pin 34 is supported in the lugs 27 and on which is fulcrumed the disk head 31. A pin 35 is carried on said disk head and on which is fulcrumed one end of the link 40, 35 the lower end of which latter is fulcrumed by means of the pin 41 to the slide 42. The latter is guided in the guide 26 and carries at its lower end the punch 43.

The bolster bed 25 carries the bolster 45 40 which is detachably held in place by the clamping bolts 46, adjusted by the operating handle 48 as fully described in United States Patent #241,617, dated May 17, 1881.

The bolster 45 carries the female die 44 45 that coacts with the punch 43.

A stripper block 47 is fastened to the frame of the machine and adjustably carries the strippers 49.

Fulcrum pins 50 are in threaded engage- 50 ment with the members 22 of the frame and carry the double yoke frame having the upper member 51 and the lower member 52. The upper and lower members are joined to form the leg 53 and the leg 54. In the leg

53 is formed a bearing 55 for the pin 50 55 and in the leg 54 is formed a bearing 56 for the other pin 50.

A bolt 60 connects the members 51 and 52 of the double yoke frame.

The member 54 of the double yoke frame 60 has formed therewith the journal bearing 64 and the leg 54 has extending therefrom the end portion 65 practically at right angles thereto.

A spindle 66 has one end journaled in the 65 end portion 65 and the other end is journaled in the bearing 64.

A cross bar 67 with the operating handles 68 is fastened to one end of the spindle 66 and a worm 70 is formed at the other end of 70 said spindle.

A worm wheel 73 is supported on the bolt 60 and meshes with the worm 70.

A cam 74 supported on the belt 60 is fas- 75 tened to the worm wheel 73 by means of the screws 75.

To operate the press the female die 44 is secured to the bolster 45 and the punch 43 is fastened to the slide 42. The operator then determines the end of the down stroke 80 of the said punch 43. The operating han- 85 dles 68 are then used to adjust the location of the cam 74, and the edge of said cam is made to bear against the edge of the foot lever 30, when said punch is at the end of its down stroke. The edge of the cam is preferably an harmonic curve or in the form of an Archimedean spiral, although it may be of other curvature. By turning the worm 70 the worm wheel 73 positions the cam 74 90 in exactly the correct location. The cam performs the function of a stop for the foot lever. The pins 50 allow the yoke support- 95 ed thereon to adjust itself in proper position for the various positions in which the said cam may be placed. It will be noted that the operating handles 68 are located adja- 100 cent to the frame of the machine and adja- cent to the handle 48, so that both are within easy reach of the user of the machine.

Having described our invention, what we desire to secure by Letters Patent and claim is:

1. In an apparatus of the character de- 105 scribed the combination of a reciprocating element, a frame for the element, a lever ful- crumed in the frame, a connection between one end of the lever and said element, a cam

positioned in the path of the element and means to adjust the cam to different positions to control the strokes of said element.

2. In an apparatus of the character described the combination of a slide, a punch for the slide, a frame with a guide for the slide, a lever fulcrumed in the frame, a connection between one end of the lever and said slide, a yoke pivoted to the frame, a cam pivoted to the yoke with its edge in the path of said lever and means to adjust the cam.

3. In an apparatus of the character described the combination of a frame having a guide, a slide guided in said guide, a foot lever pivoted in said frame, a link connecting one end of the foot lever and said slide, a yoke pivoted to the frame, a bolt connecting a pair of members of the yoke, a worm wheel and a cam supported on the bolt, means connecting the wheel and cam, a

spindle supported in bearings on the yoke, a worm at one end of the spindle meshing with the worm wheel and an operating handle at the other end of the spindle.

25

4. In an apparatus of the character described the combination of a frame having a guide, a slide guided in said guide, a foot lever pivoted in said frame, a connection between one end of the lever and said slide, an element pivoted to the frame, and an adjustable cam carried by said element and located in the path of said foot lever.

Signed at Newark in the county of Essex and State of New Jersey this 15th day of December A. D. 1913.

WILLIAM H. CHAPMAN.
